UNITED STATES PATENT OFFICE.

ANTHONY M. CUNHA, OF PROVIDENCE, RHODE ISLAND.

WRENCH.

1,370,194.

Specification of Letters Patent.

Patented Mar. 1, 1921.

Application filed July 1, 1919. Serial No. 307,908.

To all whom it may concern:

Be it known that I, ANTHONY M. CUNHA, a citizen of the United States, and resident of the city of Providence, in the county of Providence and State of Rhode Island, have invented certain new and useful Improvements in Wrenches, of which the following is a specification.

This invention relates to so-called socket wrenches and more particularly to an auxiliary detachable handle for a socket wrench, and the object of this invention is to provide such an auxiliary handle of simple and practical construction which is adapted to be readily connected to and disconnected from the main wrench to complete the forming of a T-shaped operating handle for a wrench.

With these and other objects in view, the invention consists of certain novel features 20 of construction, as will be more fully described, and particularly pointed out in the appended claims.

In the accompanying drawings:

Figure 1— is a plan view illustrating my 25 auxiliary handle as applied to a ratchet wrench.

Fig. 2— is a side elevation of the parts shown in Fig. 1 and showing the socket head of the auxiliary handle in section.

30 Fig. 3— is a view of the under side of the socket head portion of the auxiliary handle; showing the same as applied to a wrench, the handles of both parts being broken off.

35 Fig. 4— is a perspective view of my auxiliary wrench handle detached.

Fig. 5— is a side elevation illustrating the general arrangement of the auxiliary handle in the act of being applied to a 40 wrench, but before the handles are positioned in alinement with each other.

Referring to the drawings, 10 designates the head portion of a so-called socket wrench of the ratchet type, the square hole 11 in 45 the center thereof being for the purpose of receiving the bars of the usual sockets, and this wrench head is provided with a laterally-projecting, operating handle 12.

It is found in practice that where the 50 usual long or extended bar is employed, between the wrench head and the socket members (not shown) that it is often difficult to hold this bar in an upward position while a heavy tension is being applied at 55 the end of the wrench handle 12, therefore it is found advisable in some cases to provide

a wrench with a T-handle, that is, one extending from each of the opposite sides of the head.

As it is not convenient under all circumstances to use a T-handle wrench, I have provided an auxiliary handle which may be readily connected to the regular single handled wrench, whereby a single handled wrench may be converted into a double or 65 T-handle wrench when desired.

To accomplish this in a simple and practical way I have provided a socket-shaped head 13 having side walls 14 formed of thin stock which is somewhat flexible or yieldable, the socket being open at its top and preferably provided with a bottom plate 15 to strengthen and stiffen the side walls, which bottom plate is provided with an opening 16 through which the socket operating 70 extension bars may be passed into the square 75 of the wrench head.

The side walls of this auxiliary handle head are cut away at one point forming an opening as at 17 through which the handle 80 12 of the wrench may be passed in connecting the two together, the opposite edges 18 of the side walls on the opposite sides of the opening 17 are arranged to engage opposite sides of the wrench handle 12 to assist 85 in carrying the operating strain applied through the handles.

In order to further support and stiffen these side walls about the opening 17, I have provided a bridge member 19 which extends 90 from the opening and connects the upper edge of the side walls together. The head portion of the auxiliary handle is provided with a laterally extending operating bar or handle 20 which extends substantially in 95 line with the handle 12 of the wrench when the auxiliary handle is positioned thereon in order to complete the T-shaped handle of the wrench.

The side walls 14 of the head of the auxiliary handle are shaped to form a socket to receive and frictionally engage the outer surface of the head of the wrench, so that this head will be crowded or forced between these walls into the socket and so firmly secured therein by friction and the two members may be readily disengaged by forcing the handles out of alinement with each other and cause the handle 12 to be withdrawn through the opening 17 when the wrench 110 may be used with the single handle.

The device is extremely simple, inexpen-

sive and practical in its construction, may be readily connected to and disconnected from a socket wrench without the use of screws or other adjustable binding means.

5 The foregoing description is directed solely toward the construction illustrated, but I desire it to be understood that I reserve the privilege of resorting to all the mechanical changes to which the device is 10 susceptible, the invention being defined and limited only by the terms of the appended claims.

I claim:

1. A wrench comprising a head portion 15 having an operating handle extending from one side thereof, in combination with an auxiliary handle member having a socket shaped to receive and to frictionally and rigidly retain the head portion of the main wrench, said socket having a bottom portion 20 against which the wrench head is adapted to rest and having a laterally-extending operating handle set to extend in a direction opposite to and in rigid alinement with the handle on said wrench head when the two 25 are connected.
2. A detachable auxiliary wrench handle comprising a socket-shaped head having resilient side walls formed to receive and frictionally grip and retain the head of a socket 30

wrench, said walls being provided with an opening for the passage of the wrench handle, and a bottom plate on said socket against which the wrench head sets.

3. A wrench comprising a head portion 35 having an operating handle extending from one side thereof, in combination with an auxiliary handle member having a socket head portion shaped to receive and frictionally retain the head portion of the main 40 wrench, the side wall of said socket portion being provided with an opening through which the handle of the main wrench is passed in connecting the two together, a bar extending over said opening and connecting 45 the side walls thereof, the edges of the walls on the opposite sides of said opening being arranged to engage the opposite sides of the wrench handle to assist in carrying the operating strain, said socket having an operating handle extending substantially in line with that of said wrench when positioned thereon to complete a T handle on the wrench.

In testimony whereof I affix my signature 50 in presence of one witness:

ANTHONY M. CUNHA.

Witness:

HOWARD E. BARLOW.
